UNITED STATES PATENT OFFICE.

JOSEPH L. CLEMENTS, OF DETROIT, MICHIGAN.

DESIGN FOR A HAND-TOOL.

SPECIFICATION forming part of Design No. 35,446, dated December 17, 1901.

Application filed October 15, 1901. Serial No. 78,756. Term of patent 7 years.

To all whom it may concern:

Be it known that I, JOSEPH L. CLEMENTS, a citizen of the United States, residing at Detroit, in the county of Wayne and State of Michigan, have invented and produced a certain new and original Design for a Hand-Tool, of which the following is a specification, reference being had therein to the accompanying drawings, in which—

Figure 1 is a side elevation, and Fig. 2 is a perspective view.

A is a substantially T-shaped head comprising the curved horn-shaped arm *a*, the oppositely-projecting arm *b*, and the rounded stem *c*. At the junction of these members is an enlarged portion *d* of the head, which has formed centrally therein the polygonal aper-

ture *e*. The stem *c* is provided with a curved shank *f*, which terminates in a chisel-edge *g*, while a transverse aperture *h* is formed in said shank near said edge.

The leading feature of the design consists in the T-shaped head having a horn-shaped arm and the stem provided with the curved shank.

What I claim as my invention is—

The design for a hand-tool, substantially as herein shown and described.

In testimony whereof I affix my signature in presence of two witnesses.

JOSEPH L. CLEMENTS.
